UNITED STATES PATENT OFFICE.

GILBERT S. ELLITHORPE, OF CHICAGO, ILLINOIS, ASSIGNEE, BY DIRECT AND MESNE ASSIGNMENTS, TO THE BAC-LITE CORPORATION, A CORPORATION OF ILLINOIS.

TAIL LIGHT.

Application filed November 28, 1919. Serial No. 341,051.

To all whom it may concern:

Be it known that I, GILBERT S. ELLITHORPE, a citizen of the United States of America, and a resident of Chicago, county of Cook, and State of Illinois, have invented 5 certain new and useful Improvements in Tail Lights, of which the following is a specification.

This invention relates to tail lights for 10 vehicles, and especially to the structure and form of the lamp-casing and lens. The main objects of the invention are to provide an improved and more desirable form and arrangement of casing, lens, and number-plate 15 as a whole; to provide a simplified form of holder or casing for the lamp; to provide such a casing of shallow form adapted for insertion and exchange of lamps from the lens side; to provide against dust or moisture entering the casing; to provide an improved form of lens consistent with the improved casing and adapted to serve more efficiently than lenses heretofore used; to provide such a lens for a tail light, adapted 20 to serve both as a rear danger signal and as a means of illuminating the roadway behind the vehicle in case it is desired to back up, as for instance, in turning; to provide a lens of the general character stated, of cupped 25 shape formed and adapted to insure good illumination of the number plate and to provide for a substantial degree of side lighting in addition to that usually provided for the number plate; and to provide a lens having 30 a rearward red display zone and a rearward plain part adapted to throw the main illuminating light in a manner and direction highly effective for lighting the roadway and also in a manner adapted to avoid glaring 35 or blinding effects on the eyes of a person who may chance to be in range of the main illuminating part of the light.

An illustrative embodiment of this invention is shown in the accompanying drawings, 40 in which—

Fig. 1 is a vertical axial section through the preferred form of my casing and lens.

Fig. 2 is a view of the device of Fig. 1, showing the tail light and number plate assembly as viewed from behind the vehicle.

Fig. 3 is a vertical axial section through the lens and a usual form of casing.

Fig. 4 is a rear elevation of the casing and lens of Fig. 3, assembled complete, as viewed 45 from behind the vehicle.

In the construction shown in Figs. 1 and 2, the lens 1 is secured demountably in the open face of the lamp casing 2 in which the lamp 3 is centrally held. Said casing 2 is nearly flat and is in substantially the same 60 plane with the license number plate 4.

Said lens is held in place by means of a removable resilient wire 5 resting against the outer side of a flange 6 on the edge of the lens. Said lens is substantially cup-shaped and in this embodiment is somewhat convex at the cup bottom. It is provided with a central part 7 of uncolored glass surrounded by a medial zone 8 of red glass and an outer rim 9 of plain glass. The rim 9 70 is conoidal and flares divergently from the part 8. Its outer edge terminates in the flat retaining flange 6, which is disposed radially with respect to the main axis of the lamp.

As will be seen, the danger signal is effected by the red part, and the central part facilitates and insures illuminating the roadway sufficiently to enable the driver to back the vehicle in the dark without danger of running into hidden obstacles. The outer 80 part 9 serves to throw the light on the number plate 4, as well also as for some degree of general side illumination.

The red part 8 on its back or inner side is provided with a series of annular prismatic steps 10 formed to give a somewhat prismatic effect for better concentration and direction of the light, as understood in the art. The central plain part or bull's-eye 7 is provided on its back side with a number 85 of horizontal prismatic steps 11 formed and arranged to throw the light downward somewhat onto the roadway and so as to avoid a glaring effect such as would tend to blind a person standing behind the vehicle. It is 90 to be understood that the lens may well be frosted lightly, preferably on the inner side, so as to further prevent glaring effects.

The plate-shaped casing 2 comprises a flat body part with a flange 12 turned first 100 toward the vehicle somewhat at 13 and then outward to receive the lens rim 6. The extremity of said flange 12 is turned inward at 14 to engage the resilient locking ring 5. Said ring is open at 15 to facilitate 105 removal. A packing ring 16 rests in the groove at 13 and provides a dust-tight moisture-excluding seat for the lens 1.

The casing body is centrally apertured and fitted with a socket 17 for said lamp 110

3. The socket and lamp are so proportioned and designed that the light rays emanate from a point or zone well beyond or back of the rim 12, so that the plate 4 may be well lighted.

Said socket 17 also extends a considerable distance in the opposite direction, that is to say, toward the vehicle, and projects through a supporting plate 18, apertured 10 therefor at 19, to which it is rigidly secured. The electrical connections for said socket are the same as are customarily used for tail lights. The number plate 4 is secured detachably to the lower edge of 15 plate 18 by any suitable means as shown at 20.

Referring to Figs. 3 and 4, showing my improved lens as applied to casings of the general form heretofore commonly used, the 20 casing 21 comprises a flat body part 22, provided with a cylindrical flange or wall 23, the outer edge of which is turned inward to engage the locking ring 5. Said wall part 23 is provided with a transparent window 24 to illuminate the number plate, not shown in this view. This wall 23 is also provided with an inwardly projecting peripheral shoulder 25, spaced somewhat from the edge to form a bearing seat for the lens rim 6. 30 The socket 26 is mounted rigidly in the back wall 22. The other numerals on Figs. 3 and 4 have the same significance as on Figs. 1 and 2.

It is to be noted that in the preferred 35 form, that is to say in the flat casing structure of Fig. 1, the device is sealed tightly, not only at the edge of the lens by the packing ring 6, but the door or window 24 of Fig. 4 is eliminated, and the lamp is attachable from the inside when the lens is off instead of being attachable from the outside, the catch 27 being inside the casing in Fig. 1 and outside in Fig. 4. This not

only prevents rust inside the casing but more important still, protects the inner side 45 of the lens from becoming fouled with dust. The flat type of casing is economical of materials and is easy to make. The device as a whole is ornamental and is compact in form.

It is to be understood that the term lens as herein used is intended to apply to such part or parts of the device as transmit the light emanating from the lamp.

Although but one specific embodiment of 55 this tail light invention as a whole, and only one application of the new lens with an old casing, are herein shown and described, it is to be understood that numerous details of the constructions shown may 60 be altered or omitted without departing from the spirit of this invention as defined by the following claims.

I claim:

1. A vehicle tail light lens comprising a 65 convex part including a centrally located plain illuminating part and a surrounding colored annular signal part, the colored part having its inner face prismatically stepped to converge the light rays, and the plain part having its inner face prismatically stepped horizontally to throw the light 70 diagonally downward to illuminate the roadway.

2. A vehicle tail light lens including a 75 red danger signal part and a plain illuminating part, the red part having its inner face prismatically stepped to converge the light rays and the plain part having its inner face prismatically stepped horizontally to 80 throw the light diagonally downward to illuminate the roadway.

Signed at Chicago this 26th day of November, 1919.

GILBERT S. ELLITHORPE.
